UNITED STATES PATENT OFFICE.

JOHN SAWCHYN, OF PASSAIC, NEW JERSEY.

PISTOL-SWORD.

1,283,321.

Specification of Letters Patent.

Patented Oct. 29, 1918.

Application filed August 28, 1918. Serial No. 251,771.

To all whom it may concern:

Be it known that I, JOHN SAWCHYN, a subject of the Emperor of Austria, residing at Passaic, in the county of Passaic and State 5 of New Jersey, have invented certain new and useful Improvements in Pistol-Swords, of which the following is a specification.

The primary object of the invention is the provision of a sword adapted for war purposes and provided with pistol-holding means whereby an automatic pistol is operatively carried within the hilt of the sword ready for immediate use when required.

A further object of the invention is the provision of a sword adapted for readily carrying a pistol adapted for immediate use, the sword being easy and inexpensive to manufacture and only slightly heavier than the usual Army sword or saber.

With these general objects in view, the invention consists in the combination and arrangement of parts hereinafter fully described in connection with the accompanying drawings, and in which like reference characters designate corresponding parts throughout the several views.

In the drawings,

Figure 1 is a side elevation with parts broken away;

Fig. 2 is a top plan view thereof with the swinging portion of the grip illustrated by dotted lines in its open position;

Fig. 3 is a view similar to Fig. 1 with parts broken away, illustrating the pistol positioned within the hilt with a portion of the pistol barrel broken away;

Figs. 4 and 5 are transverse sectional views of the invention taken upon lines IV—IV and V—V of Fig. 1; and

Fig. 6 is a rear elevational view of the invention.

My invention includes a sword having a blade 10 provided with a hilt consisting of a two-part grip 11 having a curved hand 45 guard 12 extended as at 13 adjacent the base of the blade 10 forming a pommel. The main portion 14 of the grip 11 has a blade 10 integrally carried thereby and projecting forwardly thereof through the guard extension 13, which extension is secured by means of screws 15 to said grip portion or section 14. The rear free end of the guard 12 is secured by means of screws 16 to the curved butt or angular free end 17 of the 55 grip section 14.

The other or cover section 18 of the grip 11 is hinged for opening and closing against the section 14 by means of a pivot 19 carried by the section 18 and extending through an inwardly projecting ledge 20 integrally 60 formed upon the hand guard 12 adjacent its point of attachment with the butt 17. The butt 17 of the grip section 14 is secured in flat engagement with the said ledge 20 while a slot 21 in the extension 13 at the opposite 65 end of the hand guard accommodates the blade 10 projecting therethrough.

The grip 11 is provided with a protuberance within the hand guard 12 consisting of housing portions 22 and 23 carried by the 70 grip sections 14 and 18 respectively. These housing portions when closed form a housing having a receiving chamber 24 which taken together with a chamber portion 25 formed in the grip sections 14 and 18 are 75 adapted for the removable reception of automatic pistols 26. The barrel 27 of the pistol is longitudinally positioned within the grip 11 of the hilt and a perforation 28 through the extension 13 at one side of the blade 10 80 is adapted for alinement with the bore 29 of the barrel 27 when the pistol is mounted within the hilt. The muzzle of the barrel 27 frictionally engages the inner face of the extension 13 and the bore 29 being of 85 slightly less diameter than the perforation 28, the bullets from the pistol will freely pass through the said perforation.

An opening 30 is provided in the side of the grip section 14 through which the extracted shells are adapted to pass from the pistol barrel 27 while a finger-receiving opening 31 is provided in the housing section 23 for gaining access to the trigger 32 of the pistol 26, it being understood that 90 the stock 33 of the pistol is snugly engaged within the chamber 24 with the barrel 27 in the chamber 25 when the section 18 is closed with the device assembled. A resilient latch 34 is carried by one side of the 100 extension 13 having a wedge-shaped retainer 35 extending through a slot 36 in said extension and adapted for overlying the outer face of the swinging section 18 of the grip 11 when closed. The housing sections 105 22 and 23 are preferably formed integral with the sections 14 and 18 respectively of the grip 11, and it will be seen that upon releasing the latch 34, the section 18 may be 110 swung outwardly as indicated by dotted

lines in Fig. 2 of the drawings and at which times the pistol 26 may be readily removed from the chambers 24, 25 of the hilt 11.

The hilt 11 may be readily grasped for 5 wielding the blade 10 and whenever desired, the pistol 26 may be positioned within the hilt for immediate use in firing by pulling upon the trigger 32 by means of the finger inserted through the opening 31. The pistol is entirely protected when incased in this 10 manner within the grip of the sword, and the invention provides a double weapon that is light in weight and readily serviceable as either a sword or pistol when desired.

15 What I claim as new is:—

1. A pistol sword comprising a grip formed of a main section and a pivoted section and provided with a pistol-receiving chamber therein, a curved hand guard secured at one end to the butt of the main grip section and having an extension at its 20 opposite end forming a pommel secured to the forward end of the main grip section, a blade carried by the forward end of said 25 main section extending through said extension, mounting means upon the guard for said pivotal section, a retaining latch for the pivotal section carried by said guard

extension, the said extension having a perforation therethrough adjacent the blade 30 adapted for alinement with the firing barrel of a pistol when positioned in said chamber.

2. A pistol sword comprising a hilt having a grip provided with a pistol-receiving chamber therein, a hand guard connected to 35 the opposite ends of said grip, a blade projecting from one end of the grip, the said grip being formed in two sections, pivoting means for one section of the grip provided adjacent one end of the guard, a closure- 40 retaining latch for the pivoted section of the grip provided adjacent the opposite end of the guard, one of the sections of the grip having a side opening adapted as an outlet 45 for the extracted shells from a pistol positioned within the grip and the other section of the grip having an opening adapted for accommodating the finger of the operator during the firing of the pistol, the forward end of the guard having a perforation there- 50 through in alinement with the bore of the pistol barrel for firing therethrough at one side of the said blade.

In testimony whereof I affix my signature.

JOHN SAWCHYN.
